UNITED STATES PATENT OFFICE.

EMORY S. ENSIGN, OF JAMAICA, NEW YORK.

DESIGN FOR A BOB-SLED.

59,000.

Specification for Design.

Patented Sept. 13, 1921.

Application filed February 12, 1920. Serial No. 358,152. Term of patent 7 years.

To all whom it may concern:

Be it known that I, EMORY S. ENSIGN, a citizen of the United States, and a resident of Jamaica, Long Island, in the county and State of New York, have invented a new and original and ornamental Design for Bob-Sleds, of which the following is a specification, reference being had to the accompanying drawing, forming part hereof, and in which—

Figure 1 is a plan view of a bob-sled embodying my new design.

Fig. 2 is a side elevation of the same.

I claim:

The ornamental design for a bob-sled as shown.

EMORY S. ENSIGN.
